US00D939539S

(12) **United States Design Patent** (10) Patent No.: **US D939,539 S**
 Park et al. (45) Date of Patent: **** Dec. 28, 2021**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Min-Sun Park**, Seoul (KR); **Ji-Hye Lim**, Seoul (KR); **Sung-Hyun Jang**, Seoul (KR); **Ji-Youn Han**, Seoul (KR); **Soo-Hyun Whang**, Seoul (KR)

(73) Assignee: **SAMSUNG ELECTRONICS CO., LTD.**, Suwon-si (KR)

(**) Term: **15 Years**

(21) Appl. No.: **29/647,563**

(22) Filed: **May 14, 2018**

(30) **Foreign Application Priority Data**

Nov. 15, 2017 (KR) 30-2017-0053351
 (51) LOC (13) Cl. 14-04
 (52) U.S. Cl. ..... USPC D14/486

(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outer perimeter illustrated by a pair of dashed broken lines in the drawings illustrates a display screen or portion thereof and forms no part of the claimed design. The remaining dashed broken lines in the drawings illustrate portions of the graphical user interface that form no part of the claimed design.

1 Claim, 2 Drawing Sheets
